US00D744071S

(12) **United States Design Patent**
Natoli et al.

(10) **Patent No.:** US D744,071 S
(45) **Date of Patent:** ** Nov. 24, 2015

(54) **CONNECTOR COVERING DEVICE**

- (71) Applicant: **John Mezzalingua Associates, LLC**,
Liverpool, NY (US)
- (72) Inventors: **Christopher P. Natoli**, Baldwinsville,
NY (US); **Ian Baker**, Baldwinsville, NY
(US)
- (73) Assignee: **John Mezzalingua Associates, LLC**,
Liverpool, NY (US)
- (**) Term: **14 Years**
- (21) Appl. No.: **29/469,655**
- (22) Filed: **Oct. 11, 2013**

Related U.S. Application Data

(57) **CLAIM**

The ornamental design for a connector covering device, as
shown and described.

DESCRIPTION

A portion of the disclosure of this patent document contains
or may contain material which is subject to copyright protec-
tion. The copyright owner has no objection to the photocopy
reproduction by anyone of the patent document in exactly the
form it appears in the Patent and Trademark Office patent file
or records, but otherwise reserves all copyrights whatsoever.
FIG. 1 is a right side elevation view of the connector covering
device;
FIG. 2 is a left side elevation view of the connector covering
device thereof;
FIG. 3 is a front elevation view of the connector covering
device thereof;
FIG. 4 is a rear elevation view of the connector covering
device thereof;
FIG. 5 is a top view of the connector covering device thereof;
FIG. 6 is a bottom view of the connector covering device
thereof;
FIG. 7 is a right side isometric view of the connector covering
device thereof; FIG. 8 is a left side isometric view of the
connector covering device thereof; and,
FIG. 9 is a top isometric view of the connector covering
device thereof.
The broken lines in the drawings are shown for illustrative
purposes only and form no part of the claimed design.
